[57] **CLAIM**

The ornamental design for a plant watering wand, as shown and described.

DESCRIPTION

FIG. 1 is a perspective view of a plant watering wand showing my new design;

FIG. 2 is a top plan view thereof, on an enlarged scale, the head shown separately for convenience of illustration;

FIG. 3 is a bottom plan view thereof, on an enlarged scale, the end shown separately for convenience of illustration;

FIG. 4 is a front elevational view thereof;

FIG. 5 is a rear elevational view thereof.

The device includes a leaf-shaped valve member for controlling the amount of water flowing out of the holes in the middle portion of the flower on the top end of the device.
